UNITED STATES PATENT OFFICE.

HAROLD A. RICHARDSON, OF STEELTON, PENNSYLVANIA.

GAME-BOARD.

957,800.

Specification of Letters Patent.

Patented May 10, 1910.

Application filed February 13, 1909. Serial No. 477,575.

To all whom it may concern:

Be it known that I, HAROLD A. RICHARDSON, a citizen of the United States, residing at Steelton, in the county of Dauphin and State of Pennsylvania, have invented new and useful Improvements in Game-Boards, of which the following is a specification.

My invention relates to improvements in game apparatus.

10 The primary object of the invention is the provision of an apparatus of this character in the use of which several highly amusing and instructive games may be played, the invention comprehending a game apparatus which is simple of construction and which may be manufactured and sold at a comparatively low cost.

Broadly and generally speaking the game apparatus comprises a board, a spinner, and 20 a plurality of sets of chips.

The preferred embodiments of the invention are disclosed in the accompanying drawing wherein:—

Figure 1 is a top plan view of the board 25 of my improved game apparatus. Fig. 2 is a top plan view of the spinner. Fig. 3 is a top plan view of one of each set of chips. Fig. 4 is a top plan view of a slightly modified form of the board. Fig. 5 is a top plan view of a further modified form of the board, and Fig. 6 is a top plan view of the spinner used in connection with the board disclosed in Fig. 5.

Referring to the drawings by reference 35 numerals, 1 designates the board of my improved game apparatus. The board is preferably polygonal in outline. In Fig. 1 of the drawings is shown a quadrilateral board, while in Fig. 4 is shown an octagonal board, 40 in other respects the boards being duplicates. On the upper surface of the board are delineated by broad stripes a plurality of polygonal figures 2, 3 and 4 which are of relatively different sizes and which are arranged 45 one within the other. On the quadrilateral board stripes 5, 6, 7 and 8, and on the octagonal board stripes 5^a, 5^b, 6^a, 6^b, 7^a, 7^b, and 8^a, 8^b extend from points centrally between the ends of the sides of the inner figures 2 50 to the sides of the boards, said stripes centrally intersecting the sides of the intermediate figures 3 and the outer figures 4. On the quadrilateral board stripes 9, 10, 11, and 12, and on the octagonal board stripes 9^a, 9^b, 10^a, 10^b, 11^a, 11^b, and 12^a, 12^b, extend from 55 the corners of the inner figures 2 to the cor-

ners of the boards, said stripes intersecting the intermediate figures 3 and the figures 4 at their corners. The panels 14, 15, 16, and 17 which are formed by the sides of the figures, by the stripes and by the borders, are variously colored. The panels 14 are green, panels 15 yellow, panels 16 blue, and the panels 17 red.

On the quadrilateral board numerals running from 1 to 24 inclusive appear on the stripes 5, 6, 7, 8, 9, 10, 11 and 12, said numerals being arranged at the points where the stripes intersect the figures 2, 3 and 4. On the octagonal board numerals running from 1 to 48 inclusive appear on the stripes 5^a, 5^b, 6^a, 6^b, 7^a, 7^b, 8^a, 8^b, 9^a, 9^b, 10^a, 10^b, 11^a, 11^b, 12^a and 12^b, said numerals being arranged at the points where the stripes intersect the figures 2, 3 and 4.

The spinner comprises a base 18 having delineated on its upper surface a plurality of variously colored panels 19. Numerals from 1 to 24 inclusive appear upon the panels 19 in circles 20. An arrow 21 is rotatably mounted upon the base 18 of the spinner.

Five sets of chips 22 are used, one set of chips being blue, one set red, one set green, one set yellow, and the other set white, see Fig. 3 of the drawings.

In Fig. 5 of the drawings I have illustrated a slightly modified form of the board. On the upper side of the board, which is designated by the reference numeral 23, are delineated a series of sets of panels 24, 25 and 26, each set comprising three panels. The panels 24 are red, the panels 25 white, and the panels 26 blue. Numerals from 0 to 8 inclusive appear upon the panels in circles 27. The spinner used in connection with this board comprises a base 28 on the upper surface of which are delineated a plurality of variously colored panels 29. Numerals 0, 1, 2, 3, 4, 5, 6, 7, 8 and 12 appear upon the panels 29 in circles 30. An arrow 31 is rotatably mounted upon the base 28 of the spinner.

Among the games which may be played in the use of my improved game apparatus are tit-tat-toe, three in a row, dickory dock, automobile race, and banking.

In playing tit-tat-toe each player starts by selecting one set of three chips, the players alternately placing a chip on one of the numbers appearing on the board, each player attempting to arrange three of his

chips in a straight line. The player who succeeds in placing three of his chips in a straight line, claims one of the chips of his opponent and wins the game. This game 5 can be played with the spinner and when so played the players alternately rotate the arrow of the spinner and place a chip on that number of the board corresponding to the number of the spinner at which the arrow 10 stopped. If the arrow should stop at a number already covered, the player who rotated the arrow loses his turn.

In playing dickory dock each player selects a set of four or six chips. The players 15 alternately rotate the arrow of the spinner and place the chips on the numbers of the board corresponding with the numbers of the spinner at which the arrow stops. When one player succeeds in placing all of 20 his chips on the board he exclaims dickory dock. The players then add the numbers covered by their respective chips and the player having the largest total is the winner. If, during the game, the arrow should 25 stop at a number already covered the player who rotated the arrow loses his turn.

The game of automobile race is played in the following manner: Each player selects a set of eight chips and one of the figures 2, 30 3 and 4, the players alternately rotating the arrow of the spinner. If the arrow stops on a number corresponding to a number in the square selected by the player who rotated the arrow, he places a chip on such 35 number of his square. If the arrow does not stop on a number corresponding to a number on the square of the player who rotated the arrow, such player loses his turn. The game is won by the player who succeeds 40 in first placing chips on all the numbers of his square.

The game of banking may be played by any number of persons and includes a banker who has charge of the game and operates 45 the spinner for the players. The players each select a number of chips and place a chip on one of the colored panels of the board. When all have played the banker rotates the arrow. The player who placed 50 his chip on the panel of the board which corresponds in color to the panel over which the arrow stops wins, and the others lose.

In playing tit-tat-toe with the board illustrated in Fig. 5 of the drawings, each player 55 selects four counters and attempts to place three of his counters in a straight line, plac-

ing all of his counters on the board. If all of the chips have been placed on the board and neither of the players has succeeded in arranging three of his chips in a row, the 60 player whose turn it is removes one of his opponent's chips to the vacant space on the board and places one of his chips on the space from which his opponent's chip was removed. The game is thus played until one of the players succeeds in placing 65 three of his chips in a row. In playing this game with the spinner each player rotates the arrow of the spinner and places a chip over that number of the board which corresponds to that number of the spinner at which the arrow stops and so on until one of the players has succeeded in placing three of his chips in a row. If the arrow of the spinner stops at number 12, the player who 70 rotated the arrow wins the game.

While I have described the invention, together with the apparatus which I now consider to be the best embodiment thereof, I desire to have it understood that the apparatus shown is merely illustrative and that such changes may be made when desired as are within the scope of the claims.

Having thus described the invention, what is claimed as new is:—

1. The herein described game board having a plurality of figures delineated on its upper surface, the figures being arranged one within the other and forming panels therebetween which are variously colored, 80 and numbers appearing on the figures.

2. The herein described polygonal game board having a plurality of polygonal figures delineated on its upper surface and arranged one within the other, stripes extending 90 from the corners of the inner figure to the corners of the board, said stripes intersecting the other figures at their corners, stripes extending from the sides of the inner figure to the sides of the board, said last-named stripes centrally intersecting the sides of the other figures, the figures and stripes providing panels which are variously colored, and numbers appearing on all of the figures where they are intersected by the 105 stripes.

In testimony whereof I affix my signature in presence of two witnesses.

HAROLD A. RICHARDSON.
